UNITED STATES PATENT OFFICE.

WILLIAM GOLDIE, OF WILKINSBURG, PENNSYLVANIA.

REINFORCING MEANS FOR CONCRETE STRUCTURES.

1,344,942.

Specification of Letters Patent. Patented June 29, 1920.

Application filed July 10, 1918. Serial No. 244,237.

To all whom it may concern:

Be it known that I, WILLIAM GOLDIE, a citizen of the United States, and resident of Wilkinsburg, in the county of Allegheny 5 and State of Pennsylvania, have invented a new and useful Improvement in Reinforcing Means for Concrete Structures; and I do hereby declare the following to be a full, clear, and exact description thereof.

10 My invention relates to reinforcing structures for concrete, and is particularly concerned with a structure of this character which is adapted to reinforce the concrete against compression or tension strains coming in either direction vertically to the plane 15 of the structure; for example, in ship construction, it is obvious that the strains upon the ship's bottom or sides may be at one time exerted from the outside and at other times 20 from the inside of the ship, or there may be certain strains on the vessel caused by action of the sea against the outside; whereas, on the other hand, the bottom and sides 25 of the ship require to resist load strains or other expansion strains exerted from the interior of the ship.

However, it is to be understood that the invention is not alone applicable to ship construction, but may be used in any relation 30 where resistance or reinforcing against varying strains having varying points of application is to be assured.

In one of its main aspects the invention contemplates the placing or positioning of 35 the reinforcing members near the opposite surfaces of the reinforced wall or structure, respectively. The invention further contemplates the intimate securing together of these separate reinforcing frames, as well as 40 the definite spacing apart of the same. The connecting and spacing members also form reinforcing members for the concrete, and serve as further interlocking engaging means with the concrete, so that when the concrete 45 is molded to the reinforcing structure, it will be intimately interlocked and connected therewith at a great number of points sufficiently separated to permit the formation 50 of more or less extensive masses of concrete uniting the masses of concrete lying within and around the reinforcing structure.

With these objects in view, the invention consists in a construction and arrangement of parts, a preferred embodiment of which

is illustrated in the accompanying drawings, 55 in which Figure 1 is a fragmentary plan view of a section of one of the reinforcing frames; Fig. 2 is a sectional view on the line 2-2, Fig. 1; Fig. 3 is a sectional view on the line 3-3, Fig. 1; Figs. 4 and 5 illustrate 60 in perspective modified forms of spanner members extending between the two frames; Fig. 6 is a perspective view of one of the wedge or spacing members; Fig. 7 is a view 65 similar to Fig. 2, showing a modified form of spanner member, extending between the frames; Fig. 8 is a view of parts shown in Fig. 7, taken on a section transversely to said figure; Fig. 9 illustrates a further modification of the spanner member; and Fig. 10 is 70 a perspective detail view of this modified spanner member.

In the embodiment of my invention, as illustrated in Figs. 1 and 2, the main reinforcing members are rods 1, which consist of 75 a web 1^a and the flanges 3 extending laterally from top to bottom of said web. These flanges 3, as shown in section in Fig. 2, form preferably dovetailed recesses or grooves extending along the sides of the reinforcing 80 bars 1. It will be obvious from an inspection of this form of reinforcing bar that it possesses great strength for the minimum amount of metal in cross section. In other words, it affords an unusually strong, but 85 very light, reinforcing member, and has the additional advantage that the concrete surrounding the same may interlock with the dovetailed recesses formed by the flanges 3. The transverse reinforcing members 2 of the 90 reinforcing structure are illustrated in cross-section in Fig. 3, which consists preferably of a pair of channel members, each channel member having the vertical web 4, and each 95 having the laterally extending flanges 5. Consequently, these transverse members also present laterally opening grooves between the upper and lower flanges 5, which serve to interlock the concrete intimately therewith. These channel members may be secured together by means of rivets 6, if desired, but it is to be understood that the main object of thus placing the channel members back to back, as shown, is to prevent engagement of the concrete with the 100 smooth vertical walls of the bottom wedge of these channel members. It is to be understood, however, that the form and construc-

tion of this transverse reinforcing member may be varied in different ways, namely, it may consist of a T-bar, or it may be rolled in one unitary structure presenting the channels on either side.

However, one of the main features of my invention is more clearly illustrated in Figs. 2, 3, 7 and 8. This is the fact that the reinforcing structure, taken as a whole, consists of two distinct and separate frames, each frame comprising the main frame members 1, and the transverse frame members 2 intimately and rigidly secured to the main members. These two separate and distinct reinforcing frames are held spaced apart by means of intermediate uniting and spacing members, to be described, so that, as indicated in Fig. 2 of the drawing, the upper reinforcing frame shown therein lies just within the upper surface 7 of the surrounding concrete mass 8, whereas the lower frame lies just within the lower surface 9 of this concrete mass. The result of this construction and arrangement is that the reinforcing effect of each of these spaced frames is exerted at and within the critical planes of the reinforced concrete structure as a whole, to effectively resist bending or other strains directed against the opposite surfaces of the structure, respectively, for example, if in the structure illustrated in Fig. 2 the load strains be exerted from above, the upper reinforcing frame becomes a compression resisting member, whereas, the lower frame becomes an expansion resisting member, and when the bending force is directed against the bottom of the reinforcing structure illustrated in Fig. 2, the lower reinforcing frame becomes the compression resisting member, whereas, the upper reinforcing member becomes the expansion resisting member.

Furthermore, these two frames are themselves reinforced and strengthened and become in effect a truss structure when united together by the spanner members, and the wedge members now to be described.

Referring, for example, to Figs. 2 and 3, it will be noted that I employ spanner members such as 10, each having an end flange 11 at either end to engage the flanges 3 of the main frame 1. Thus, the member and also frames, as here shown, are held at a limited distance apart, limited by the length 55 of the spanner members 10. One of these spanner members is illustrated in perspective in Fig. 4, and as there shown, its body portion is provided with an opening 12 to facilitate the flow of the concrete through 60 and around the spanner member. A modified form of this spanner member is illustrated in Fig. 5, and consists of the body portion 13 and the end flange 14, but in this case the body portion is reinforced by the 65 presence of a bent beam 15 extending lon-

gitudinally of said spanner member and formed by bending up the center of the blank which forms the spanner member. Then the flanges 14 may be formed by bending down the ends of the laterally extending 70 portions of the body part of the spanner to form the hooks for engagement with the flanges 3 of the main frame members 1.

In conjunction with these spanner members 10 and 13, I also employ expanding 75 wedges such as 16, see Figs. 2, 3 and 6. These wedge members comprise a bent blank, which, when formed, has its legs spread apart. A curved depression 17 is formed at the junction of the legs for engagement with the curved face of the frame members 1, and the ends of the legs of this wedge member are provided with curved depressions 18 for engaging the curved face of the frame member with the main frame 80 members of the opposite frame. By placing these wedge members between the main frame members, as shown in Figs. 2 and 3, and then forcing the legs of the wedge member together, I provide a very effective spacing or expanding member between the two frames which coöperate with the spanner members 10 to hold the frames rigidly at a predetermined distance apart.

In Figs. 7 to 10, inclusive, of the drawings 95 I show a modified form of a combined spacing and spanner member to be used between the main frame members. In this case, the framework again comprises the main frame members 1 and the transverse frame members 2, such as illustrated and described heretofore. Whereas, the combined spacer and spanner member consists, as shown in perspective in Fig. 10, of a body or base member 19, having the curved ends 20 100 adapted to engage between the opposite curved faces of the main frame members 1, and extending laterally from this body member 19 are the legs or arms 21, which, as shown in Figs. 7 to 9, inclusive, may be 105 bent about or curved around the outer faces of the main frame members and, if desired, the ends of these legs may be bent beneath the flanges 3 shown at 22, Figs. 7 and 9.

It will be seen, therefore, that this combined form of spanner and wedge member serves both as a spacing member to hold the main frames definitely spaced apart and also a binding or spanner member to bind the frames one to the other. These combined spanner and spacing members may be provided in their body portions with apertures or openings 23 to permit of free flow of the concrete around these parts and to interlock the concrete firmly and intimately therewith.

While I have herein described particular embodiments of my invention and have specified a particular construction and arrangement of parts, it is to be understood 130

that the invention may be altered in details of construction and arrangement within the scope of the appended claims.

What I claim is:

- 5 1. In a concrete reinforcing structure, the combination with a plurality of reinforcing frames, each consisting of main and auxiliary reinforcing members, said members presenting laterally extending flanges, means for holding said frames spaced apart at a predetermined distance, said means consisting of spanner members for limiting the distance apart of the frames, wedging or expander members interposed between the
- 10 15 frames for wedging said members apart within the limits of said spanner members.
- 20 2. In a concrete reinforcing structure, the combination with a plurality of reinforcing frames, each comprising substantially parallel channel members and transversely arranged reinforcing members rigidly engaged therewith, of holding means for holding said frames spaced apart at a predetermined distance, said means comprising members having hooks or flanges adapted to engage the flanges of the opposite
- 25

channel members of said frames, respectively, and wedge members adapted to be interposed between said frames which are connected by said spanner members to 30 wedge said frames apart within the limits permitted by said holding members.

3. In a concrete reinforcing structure, the combination with a plurality of reinforcing frames, each comprising substantially parallel channel members and transversely arranged reinforcing members rigidly engaged therewith, of a plurality of holding members having hook or flange ends adapted to span said frames and engage over the 35 adjacent flanges of said channel members to limit the spacing apart of said frames, and a plurality of expandible braces adapted to be expanded between said frames to bind the same rigidly in engagement with said 40 holding members.

In testimony whereof I, the said WILLIAM GOLDIE, have hereunto set my hand.

WILLIAM GOLDIE.
